UNITED STATES PATENT OFFICE.

JOHN J. HARDY, OF CHICAGO, ILLINOIS, ASSIGNOR OF ONE-HALF TO
CHRISTIAN ROPP, OF SAME PLACE.

GYROSCOPIC TOP.

SPECIFICATION forming part of Letters Patent No. 484,960, dated October 25, 1892.

Application filed January 18, 1892. Serial No. 418,548. (No model.)

To all whom it may concern:

Be it known that I, JOHN J. HARDY, of Chicago, in the county of Cook and State of Illinois, have invented certain new and useful Improvements in Gyroscopic Tops; and I do hereby declare that the following is a full, clear, and exact description thereof, reference being had to the accompanying drawings, and to the letters of reference marked thereon, which form a part of this specification.

This invention relates to a novel toy in the nature of a spinning-top, but which resembles, also, the device known as a gyroscope, wherein the revolved body is so constructed or arranged that it may stand or will be supported with its axis of revolution in other than a vertical position.

The invention consists in the matters hereinafter described, and pointed out in the appended claims.

A device embodying my invention embraces as its main features an exterior shell or casing and an interior heavy body mounted to rotate within the exterior shell, having its parts symmetrically disposed with reference to the center of rotation, while the exterior is symmetrically arranged with reference to the axis of rotation of the said revolving body. The said shell is provided with a rigidly attached supporting spindle or head, preferably of spherical form, arranged in alignment with the axis of rotation of the interior heavy body, and a part or shaft rigid with the body extends through the shell in the said axis of rotation and is provided outside of the said shell with a cylindrical part or drum, on which a string or cord may be wound to be withdrawn therefrom and give rapid rotary motion to the heavy body, or with other means by which rotary motion may be imparted to said heavy body.

The device constructed of the parts named may be used as an ordinary top, in which case it may rest either upon the spindle of the shell or the projecting spindle attached to the interior heavy body while spinning, or the spherical end of the spindle attached to the shell may be placed on any suitable support, when the article will stand in an inclined position or gyrate to its point of support in the same manner as an ordinary gyroscope.

The invention may be more readily understood by reference to the accompanying drawings, in which—

Figure 1 is a view in central vertical section of a device embodying my invention, the same being shown when standing in a vertical position and resting upon the spindle of the outer shell. Fig. 2 is a sectional view of the same, taken on line 2 2 of Fig. 1. Fig. 3 is a side view of the device when resting on the spindle of the inner or heavy body. Fig. 4 shows the device standing with its axis of rotation horizontal by the resting of the spindle attached to the outer shell or casing on the stationary support or post. Fig. 5 shows the device in a similar position when supported in the loop of a string.

As shown in said drawings, A indicates the exterior casing or shell, herein shown as made of spherical form; B, the interior heavy body or top proper, herein shown as of wheel or disk form, and C a center shaft or spindle mounted within the shell A and to which disk B is secured. Said spindle C is engaged at one end with a block or plug D, secured to the shell A, and at its opposite end passes through a bearing E, secured to the shell at the side thereof diametrically opposite the plug D. The said shaft is arranged to extend beyond or outside of the shell through a hole in the same and having at its outer end a drum F, from which a cord may be wound for the purpose of giving rotary motion to the top. The end of the spindle C, engaged with the bearing on plug D, is preferably made conical or pointed, as shown, and rests in a V-shaped step or bearing-recess in said plug, so that a minimum amount of friction will be produced in the rotation of the spindle relatively to the shell. A collar on the said spindle, resting against the bearing E, serves to prevent the spindle from being shifted endwise out of place. The extreme end of the spindle C is preferably formed into a conical bearing C', which may rest on the surface which supports the device, as shown in Fig. 3.

G is a bearing-spindle secured to and projecting from the shell A in alignment with the spindle C, said spindle G being provided with a spherical head or bearing-surface g,

forming a spherical bearing-surface for engagement with the support on which the article rests under some circumstances. In the practical construction shown the spindle G is secured to the shell by means of a screw-threaded shank on the plug D, which shank passes through a hole in the shell A and enters a screw-threaded recess in the spindle G.

In operating or spinning the gyroscopic top 10 described it is held in one hand by grasping the shell A and then applying force to the projecting end of the spindle C in a manner to give rapid rotary motion to the top B, attached to said spindle. The drum F, around 15 which a string may be wound and from which it may be withdrawn in the same manner, as in spinning an ordinary top, forms a convenient means of giving such rotary motion to the top B. When the top B has been put in 20 motion, the article may then be placed on a support or supporting-surface with either the head g or point C downward. In the latter case the exterior shell will practically 25 partake of the motion of the inner top, and the article will spin like an ordinary top. If placed with the head g downward, the article will spin to some extent like an ordinary top; but by reason of the friction between the head g and the surface on which 30 it rests the shell will be retarded relatively to the heavy body. Inasmuch, however, as there will be much less friction developed between the spindle C and the shell than there would be between said spindle and the 35 surface on which it rests, owing to the accurate mechanical adjustment or fit which may be employed in making the bearing-surfaces, the motion of the top proper will continue a much longer time than would a top as ordinarily constructed, and in fact the article 40 will still retain its upright position after the exterior shell has ceased to revolve with the same, it being of course understood that after the speed of rotation of the interior top has 45 been so reduced that it is not sufficient to overcome the friction between the head g and the supporting-surface the outer shell will no longer revolve. Fig. 1 shows the device while standing on the said head g.

50 Fig. 4 shows the device used in the same manner as a gyroscope II in said figure, showing a supporting-post having a depression or recess h, at its top, in which the head g is allowed to rest after the interior heavy body 55 has been put in rotation. The article thus supported will revolve about the post II while remaining with its axis in a horizontal or angular position in which it has been placed in the same manner as the well-known gyro- 60 scope.

In Fig. 5 the article is shown as being spun with its axis of rotation horizontal, by means of a string or cord I, the loop of which is engaged with a groove formed between the head 65 g and the body of the spindle G.

When the article is allowed to rest verti-

cally on a convex surface, as indicated in dotted lines at J, Fig. 1—such, for instance, as the inner surface of a smooth saucer—the article will describe a movement in a circle or will, 70 in other words, gyrate or revolve about a central axis of revolution.

The article made as described is obviously capable of uses in other ways calculated to amuse or instruct—as, for instance, when 75 holding it in the hand after having put the interior top in rapid rotation a considerable and perceptible effort is required to change the angular position of the article, so that the tendency of a rotating body to continue to 80 rotate in the same plane may be well illustrated by thus holding and moving it.

While I have shown the outer shell as of spherical form and the inner revolvable body in the form of a disk, yet it is obvious that 85 these parts may be varied in shape or made of any desired form without departure from my invention.

By extending the spindle through the shell, securing the drum thereon, and providing the 90 spindle with a conical bearing-point outside of the drum a simple and desirable means of giving motion to the spindle is afforded, and at the same time the top is adapted to be spun on either end, as desired. An important advantage is gained by the employment of the 95 drum, arranged as described, in connection with a continuous or spherical shell, as will be obvious from the fact that in winding the 100 cord on the drum the shell may be grasped or held between the thumb of that hand and the shell, and the cord may be then easily and quickly wound by the use of the other hand.

As hereinbefore set forth, the rounded or spherical head g affords such degree of frictional contact with the surface upon which it rests that the rotation of the shell is retarded. The extent of retardation will vary according 110 to circumstances, and when the frictional resistance to the turning of the shell is so great that it has little or no rotation the article has the appearance of standing on the head g without apparent reason. This will commonly 115 be the case when the top is supported on a pedestal, the shell at such times rotating very slowly or not at all, and thereby producing a puzzling or mystifying effect and greatly increasing the value of the article as a scientific 120 toy or curiosity.

I claim as my invention—

1. The gyroscopic top described, comprising an outer continuous shell having a rounded or spherical head projecting therefrom and rigid therewith and a top mounted therein with its axial rotative shaft in line with said projecting head, said shaft extending through the shell at a point opposite the head and being provided externally to the shell with a 125 rigidly-attached spool or drum for a spinning-cord, substantially as described.

2. The gyroscopic top described, comprising an outer continuous shell having a rounded or spherical head projecting therefrom and rigid therewith and a top mounted therein with its axial rotative shaft in line with said projecting head, said shaft extending through the shell at a point opposite the head and being provided externally to the shell with a rigidly-attached spool or drum for a spinning- cord and an axial bearing point at the outer end of the spool, substantially as described.
- In testimony that I claim the foregoing as my invention I affix my signature in presence of two witnesses.

JOHN J. HARDY.
